UNITED STATES PATENT OFFICE.

MARK LANG, OF TAFT, CALIFORNIA.

PUMP.

1,075,658.

Specification of Letters Patent. Patented Oct. 14, 1913.

Application filed September 27, 1912. Serial No. 722,746.

To all whom it may concern:

Be it known that I, MARK LANG, a citizen of the United States, residing at Taft, in the county of Kern and State of California, have invented a new and useful Pump, of which the following is a specification.

The present invention relates to improvements in pumps, the primary object of the invention being the provision of a pump especially adapted for use in oil wells, and is provided with a novel form of liner sleeve in which is mounted the plunger, the lower standing valve being so disposed with relation to the plunger, as to be readily removed from the tubing or casing with the plunger, by means of sucker rods, thus providing a means whereby the internal mechanism of the pump is readily reached for repairs and renewal.

A further object of the present invention is the provision of an oil well pump, in which a liner is inserted within the plunger carrying barrel thereof from the upper end of the tubing, the same being held in downward position by means of a plurality of spring locks, said locks being disposed in the path of to be engaged by the plunger when the plunger is lifted to its extreme up position, such up position being above the normal stroke movement of the plunger, thus providing a means whereby the plunger will release the liner which carries therewith the lower standing valve as well as the plunger valve, by means of pulling the sucker rods, thus permitting the ready removability of the pumping mechanism for repair and renewal.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a longitudinal sectional view through the valve portion adjacent to the standing valve and the plunger. Fig. 2 is a section taken on line 2—2 of Fig. 1. Fig. 3 is a section taken on line 3—3 of Fig. 1. Fig. 4 is a section taken on line 4—4 of Fig. 1. Fig. 5 is a section taken on line 5—5 of Fig. 1. Fig. 6 is a section taken on line 6—6 of Fig. 1.

Referring to the drawings, the numerals 1 and 1' designate respectively the upper and lower ends of the tubing between which is connected the liner and plunger carrying member of the pump.

The upper portion or nipple 3 is connected to the lower end of the tubing 1 by means of the collar or coupling sleeve 4, while the lower section 5 of the nipple is connected to the lower end of the nipple 3 by means of the collar or coupling 6, with the interposed packing ring 7 disposed between the ends of the nipples 3 and 5.

Disposed within the nipple 5 below the packing ring 7 is a flexible packing sleeve 8, and secured to the lower end of the nipple 5 is the cylindrical barrel 9, said barrel 9 being connected to the lower end of the nipple 5 by the sleeve 10. The coupling 11 is connected exteriorly of the lower end of the barrel 9 and forms the connection between it and the upper end of the tubing 1.

Slidably mounted concentrically of and within the nipples 3 and 5, the same being passed through the packing ring 7 and the rubber packing sleeve 8, with its lower end fitting snugly within the barrel 9 is the liner sleeve 12, the same being made up of one or a plurality of sections, said sections being connected together by means of the threaded joints 13 which are formed of male and female threaded ends that do not affect the diameter of the liner sleeve, either interiorly or exteriorly thereof. The lower end of the liner sleeve 12 is beveled as at 14 to fit within the conical seat 15 of the coupling 11. In order that the barrel 9 may be properly locked against rotation relatively to the coupling 11, the locking device 16 is employed and has its respective ends connected to the barrel 9 and coupling 11.

Mounted for sliding movement, but normally seating firmly within the lower end of the liner sleeve 12 is the standing valve 17, whose garbutt rod 20 is mounted slidably or concentrically through the lower plunger nut 19 of the cylindrical sleeve plunger 18, said plunger 18 being slidably mounted within the barrel 9. Carried upon the upper end of the rod 20 is a knob or button 21 which provides a means whereby when the plunger 18 is lifted for removal, it carries therewith the standing valve 17 through the medium of the engagement of the knob or button 21 with the lower nut 19 of the plunger 18. Connected in the upper end

of the plunger 18 is the valved inlet and upper plunger nut 22 whose valve cage 23 extends upwardly therefrom and provides a casing for the ball valve 24. In order to 5 operate the plunger 18 and consequently draw the liquid through the tubing 1' and the standing valve 17 and finally into the nipples 5 and 3 to the tubing 1, a rod 25 is connected to the valve cage 23 and extends 10 upward through the lifter nut 26 which is connected in the upper end of the liner sleeve 12. The upper end of the rod 25 is connected to the drive nut 27, which forms a coupling between said rod 25 and the actuating or 15 sucker rod 28. By this means the plunger 18 is properly reciprocated and normally in its reciprocation does not exceed the dot-and-dash line position Fig. 1.

In order to lock the liner sleeve against 20 upward movement during the reciprocation of the plunger 18, the diametrically disposed spring catches 30 have their lower ends connected at 29 to the nipple 3, with their free trigger ends 31 disposed within the slots 25 32 of the liner sleeve 12. Thus it will be seen that the catches 30 will lock the liner sleeve against upward movement.

Should it be desired to remove the liner sleeve 12 and the plunger 18, as well as the 30 standing valve 17 from the barrel 9, the nipples 3 and 5 and the tubing 1, the rod 28 is moved to carry with it the rod 25, until the curved portion of the cage 23 abuts the trigger ends 31 of the catches 30, thus 35 moving the same outwardly and alining the outer portion of the plunger 18 so as to hold the trigger ends 31 out of the slots 32 so that when the cage 23 engages the under side of the lifting nut 26, the complete liner 40 sleeve with the plunger 18 and standing valve 17 may be removed bodily through the tubing 1 and exteriorly of the casing to permit of the renewal or repair thereof.

The liner sleeve 12 is provided with a plurality of apertures 33 in the wall thereof to 45 provide ports of egress for the oil during its passage upwardly through the tubing 1.

From the foregoing description, taken in connection with the drawings it is evident 50 that with a liner sleeve constructed according to the present invention, that the standing valve 17 will be bodily removable and insertible within the tubing simultaneously with the liner sleeve and the plunger 18, and 55 thus the necessity for performing numerous operations, as is the present practice in the removal and insertion of the wearing parts of the pump, is overcome.

By providing the spring catches 30, it is evident that the sleeve 11 is held locked and seated, but that the too far upward movement of the casing 23 and plunger 18 will automatically release the liner sleeve so as to permit of the ready withdrawal of the same with the standing valve as heretofore 65 described.

What is claimed is:

1. A pump, having a plunger receiving barrel, a liner sleeve mounted in the barrel, and having lock receiving apertures in its 70 walls, two locking springs for the sleeve secured to the barrel and having projections upon their free ends for insertion through the apertures of the sleeve, a standing valve mounted in the lower end of and carried 75 by the liner sleeve, a plunger mounted in the liner sleeve and capable of engaging the projections of the springs to release the springs and bodily carry the liner sleeve and standing valve therewith when lifted out of 80 the barrel, and co-acting means carried by the plunger and the standing valve to insure the removal of the standing valve with the plunger.

2. A pump, having a plunger receiving 85 barrel, a liner sleeve mounted therein and having diametrically disposed slots near its upper end, a plurality of springs having their lower ends connected to the barrel, the upper free ends being provided with projections to extend through the slots to retain the liner sleeve seated within the barrel, a standing valve mounted in the lower end thereof and carried by the liner sleeve, a plunger mounted for reciprocation within 90 the liner sleeve, a sucker rod for actuating the plunger, co-acting means carried by the plunger and the standing valve to retain the standing valve relatively to the plunger and to permit the proper reciprocatory movement of the plunger, said plunger being so constructed that when moved abnormally upward it engages and moves outwardly the projections of the springs to release the springs from the liner 105 sleeve and permit the bodily removal of the liner sleeve and standing valve through the medium of the plunger and sucker rod.

In testimony that I claim the foregoing as my own, I have hereto affixed by signature 110 in the presence of two witnesses.

MARK LANG.
